UNITED STATES PATENT OFFICE.

THOMAS SPENCER MILLER, OF SOUTH ORANGE, NEW JERSEY.

LOAD-TRANSFERRING APPARATUS.

1,102,534.

Specification of Letters Patent.

Patented July 7, 1914.

Application filed October 24, 1911. Serial No. 656,510.

To all whom it may concern:

Be it known that I, THOMAS SPENCER MILLER, a citizen of the United States, residing at South Orange, in the county of Essex 5 and State of New Jersey, have invented certain new and useful Improvements in Load-Transferring Apparatus, of which the following is a specification.

My invention broadly and generally relates to new and useful improvements in load-transferring apparatus, and more particularly contemplates a transfer apparatus which can be conveniently employed for loading the contents of wagons upon rail- 15 way cars, although I desire it understood that I am not to be limited to such use, as the invention is capable of successful use for many purposes.

The invention consists in the construction 20 and arrangement of parts in operative combination to be fully described hereinafter and the novelty of which will be particularly pointed out and distinctly claimed.

I have fully and clearly illustrated one 25 embodiment of my invention in the accompanying drawings to be taken as a part of this application and wherein:

Figure 1 is a view in side elevation of a 30 structure embodying my invention; Fig. 2 is a view in end elevation of the structure shown in Fig. 1 looking from the left of the latter; Fig. 3 is an enlarged detailed view of the holding means for the hoisting and transferring carriage; Fig. 4 is an enlarged 35 detail view; Fig. 5 is a view in side elevation of the hoisting carriage; Fig. 6 is a view in end elevation of the hoisting carriage in half-section, and Fig. 7 is a detail sectional view of the hoisting block.

Referring to the drawings by characters 40 of reference, 1, 2 designate standards or uprights adapted to be set on opposite sides of a railway track 3 upon which travels a car 4 to receive the load, said standards being spaced apart a sufficient distance and so arranged relative to the track that a space is left at one side of the track within which a wagon 5 carrying the load to be transferred to the car may be drawn and stand 45 while the load is being transferred. The dimensions and structure of these standards may in a general way be said to be immaterial as long as they have sufficient rigidity and strength to perform the functions for 55 which they are employed. Specifically I

prefer to make these standards in the form of A-frames consisting of side standards 6, 7 joined at their heads and bases by transverse members 8, 9 and at intermediate points by members 10, 11, and diagonal truss members 12. When installed for use these standards are preferably, although not necessarily, inclined toward each other as indicated in Fig. 1, and are joined by transverse connecting bridge or track supporting members 13, 14 arranged parallel to each other and having their ends connected to the transverse members of the A-frames. These bridge or track members may be inclined from a point over the space occupied 60 by the wagon upward to their point of connection with the standard on the opposite side of the track from the wagon space, but I do not desire to be limited to this inclined arrangement as the track may be horizontal, if desired. The track members are spaced apart longitudinally in parallel relation so that there is a free longitudinal space between the same from end to end, for 65 a purpose to be presently described.

The supporting standards or uprights may be connected by inclined bracing members 15 as shown in Fig. 1 of the drawings. Arranged on the upper surfaces of the bridge or track supporting members are 70 main track rail sections 16 which extend from a point adjacent the lower end of the inclined members 13, 14 to a point approximately in vertical alinement with the central portion of the track upon which the 75 railway cars travel. At this point the bridge members are recessed as shown at 17, so that a depression or pocket is formed in the trackway at this point having a shoulder 80 or abutment 18 at the upper end of the 85 main rail section. Adjacent the upper end of the inclined trackway on each member 13, 14 is an inclined supporting block 19 upon which is secured a movable track rail section 20 which extends down toward and at 90 its lower end approaches the upper end of the rail section 16 heretofore described, said inclined rail section being of spring metal so that in its normal position it forms a 95 continuous joint with the main rail section, with the space or pocket in the bridge member beneath its lower end portion so that it may be depressed into said pocket below the 100 level of the main rail section in a manner 105 to be presently described. Adjacent the 110

5 pocket in each track supporting member and beneath the latter, said members are connected by means of transverse members 21, 21, which support a member 22 extending lengthwise of the track. Extending 10 through these members 22 and projecting upwardly between the members 21, 21, connecting the bridge pieces, and through openings in the bridge members are plunger rods 21^a which, at their upper ends, are connected to the lower free ends of the movable spring track sections 20, 20, said plunger rods having at their lower end portions expansive springs 23 abutting said member 22 15 and a shoulder 24 on the plunger to normally operate to force the lower ends of the spring track sections into longitudinal alignment with the main track sections. The lower end of each plunger is provided with 20 an adjustable stop in the form of nuts 25 to abut the lower face of the member 22 so that the extent of upward movement of the spring track sections may be so determined and regulated that when the movable end 25 portions of said track sections are raised, by their own resiliency and said springs, said end portions will be flush with the upper ends of the main track section. These plunger rods, in order to provide for smooth and 30 easy movement, may slide in sleeves 26 seated within the bridge pieces. The shoulder 24 preferably consists of nuts adjustably threaded onto the plunger so that by adjustment of the same the force of the spring 35 may be varied.

It will be understood that the normal position of the movable track sections is with their lower ends flush with the upper ends of the main track sections. While I may 40 make the upper track sections of resilient material such as spring metal, it is to be understood that they may be made of rigid material and the spring-operated plungers alone employed to urge said track sections 45 into their normal position.

Arranged to travel on the tracks on the spaced bridge members longitudinally of the latter is a traveling hoisting and conveying carriage 27 which is specifically illustrated 50 in Figs. 5 and 6. Specifically, although not necessarily, this carriage comprises opposite side plates 28, 28 connected by transverse bolts 29, 29 between which plates are journaled two rope sheaves 30, 30, and at the 55 upper end of the carriage are transverse axles 31, 31 upon which are mounted flanged track wheels 32 adapted to run on the trackways supported by said bridge members. Supported from said carriage is a block and 60 fall 33 including at its lower end a double sheave block 34, illustrated specifically in Fig. 7, the ropes of the fall passing through said block and over the sheaves of the traveling carriage, the free end of the rope passing 65 lengthwise of the bridge members be-

tween the same, thence over a pulley or sheave 35 journaled at the upper end of said bridge members, whence said rope may pass downward and under a sheave 36 at the lower end of the upright. The rope may be operated by any suitable draft means; that is, either mechanically or by draft animals. A stop 40 is provided on the lower end of the tracks to position the carriage 27 over the center of the cart.

The operation of the above-described embodiment of my invention in transferring a load from the wagon to a car traveling on the trackway 3 is as follows, it first being premised that the load to be transferred is a bundle of cane slung in a sling of the type generally used for this purpose. The carriage heretofore described is operated to be in position against the stop 40, as shown in full lines in Fig. 1, over the wagon supporting the load to be transferred, and the chains 37 of the sling 38 are connected to the hook 39 of the fall block. The draft line 33 of the fall connection is then taken up until the block strikes the bottom of the carriage, during which operation the carriage and load move longitudinally of the bridge members toward a point over the railway car, the pull on the draft line being continued until the running wheels of the carriage pass from the main track section 16 onto the compressible or movable track section 20, in which position the weight of the carriage and the load serves to depress said movable track sections against the resistance of their own resiliency and the plungers 21^a so that said track wheels drop behind the shoulders 18 of the recesses. By the operation just stated the carriage is held at the upper end of the inclined trackway as long as the load is supported from the carriage and the draft line 33 may be slackened off to lower the load without danger of the carriage gravitating along the trackway. When the load is unslung from the block and fall, the movable track sections 20 rise to their normal position and permit the carriage to gravitate down the inclined trackway into position to have the block and fall connected to another load. It will be understood that the force exerted upon the movable or compressible track section by the spring plungers, or their own resiliency, to raise them to normal position is sufficient to overcome the weight of the carriage, but is less than the force exerted by the weight of the carriage and load so that when the loaded carriage passes onto the movable track sections the latter are depressed, but the carriage alone would not operate to depress the track sections, and the latter operate to raise the carriage in position to gravitate along the trackway, whenever the carriage is relieved of its load. It will be apparent that the movable track section 20

and the shoulder 18 of the main track section constitute in effect a latch to lock and hold the loaded carriage at the point where the load is to be dumped or lowered.

5 While I have shown the invention as being applied to a rigid track, I do not desire to be limited to such a trackway as the invention is applicable broadly to other forms of tracks than that shown and contemplates 70 flexible and rigid tracks as being equivalents as far as this invention is concerned.

10 What I claim and desire to secure by Letters Patent of the United States is:—

15 1. A load-transferring means, comprising a trackway having a recess, a movable track-section over the recess, a load carriage on the trackway, means whereby the movable track-section moves under the weight of the carriage and load, and means for lifting 20 said track-section when the carriage is relieved of the load.

25 2. A load-transferring means, comprising a trackway having a recess, a movable track-section over the recess and movable into the same, a load carriage traveling on the trackway, and means for supporting the movable track-section under weight of the carriage but permitting the said section to enter the recess under weight of the carriage 30 and load.

35 3. A load-transferring means, comprising a trackway having a recess, a movable track-section over the recess and forming a continuation of the trackway, and movable into said recess, a load carriage traveling on the trackway, and means whereby the said movable section automatically lowers the carriage into the recess under the weight of the carriage and load, and returns the track- 40 section to normal position when the carriage is relieved of load.

45 4. A load-transferring means, comprising a trackway having a recess, a movable track-section over the recess and forming a continuation of the trackway, and movable into said recess, a load carriage traveling on the trackway, and spring means whereby the said movable section automatically lowers the carriage into the recess under the weight 50 of the carriage and load, and returns the track-section to normal position when the carriage is relieved of load.

55 5. A load-transferring means comprising a trackway, a part arranged end to end, and in alinement with the trackway, the end of said part adjacent the end of the trackway being movable below the end of said trackway, a load carriage traveling on the trackway and means for supporting the said 60 movable part under weight of the carriage but permitting the said section to be moved downward under weight of the carriage and load.

65 6. A load-transferring means comprising a trackway, a part disposed end to end with

the trackway and normally on a level with the trackway, and mounted to have its end adjacent the end of the trackway movable below the said end of the trackway, and means whereby said movable part is moved beneath the adjacent end of the trackway whereby the said end of the trackway operates as a stop to prevent travel of the carriage in one direction.

7. A load-transferring means comprising a trackway, a movable part normally in alinement with and on the same level as the trackway and mounted for movement to a point below the level of the trackway, a load carriage traveling over the trackway, 80 and means for supporting the said movable part under weight of the carriage but permitting said section to be moved below the level of the trackway under weight of the carriage and load.

8. A load-transferring device, in combination, a track, a load carriage to travel thereon, a fall block, a hoisting rope, a yielding and recovering device applied to a section of the track at its unloading point 90 whereby the carriage is locked when the load is hanging on the fall block and unlocked when unloaded.

9. A load-transferring means, comprising a trackway including a main section and a section mounted to be moved below the level of the main section, a load carriage on the trackway and a spring-operated plunger normally maintaining the movable track-section on a level with the main section.

10. A load-transferring means comprising an inclined trackway including a main section and a section normally in line with the main section but movable below the level thereof, said sections having their ends adjacent each other, a load carriage on the trackway, and means whereby the carriage and load automatically operate the movable track section to lower the carriage beneath the level of the main section so that the end of said main section adjacent the movable section operates as a stop to prevent traveling of the carriage in one direction, said means operating to raise the carriage to the level of the main section when the carriage 115 is relieved of the load.

11. A load-transferring device comprising two track sections having abutting ends one of which track sections is mounted whereby its end may be moved below the end of the adjacent section, a load carriage to travel on the trackway and means whereby the movable track section is maintained on a level with the other track section when the carriage is unloaded and on the movable section, and moves below said other section when the carriage is on said movable section and loaded.

12. A load-transferring device comprising a trackway including two track sections ar-

ranged in alinement, the end of one section being closely adjacent the end of another section, means whereby one of said sections is movable to a point below the level of the 5 other section, a load carriage traveling on the trackway, and means to maintain said track sections on the same level when the carriage is unloaded but permits the carriage and load to move said movable section 10 below the other section when the carriage is loaded.

13. A load-transferring means comprising a trackway including two sections arranged end to end and in longitudinal alinement, 15 means whereby one of said sections may be moved downward to bring its end below the adjacent end of the other section whereby said adjacent end constitutes a stop, a load carriage movable along the trackway, and 20 means whereby the end of the movable section is moved downward under the weight of the carriage and load.

14. A load-transferring means comprising a trackway including two sections arranged 25 end to end and in longitudinal alinement, means whereby one of said sections may be moved downward to bring its end below the adjacent end of the other sections whereby said adjacent end constitutes a stop, a load 30 carriage movable along the trackway, and means whereby the end of the movable section is moved downward under the weight of the carriage and load and is restored to normal position when the carriage is relieved of its load.

15. A load-transferring means comprising a trackway including two sections end to end and in longitudinal alinement, one of said sections being mounted to be moved downward to bring its end below the adjacent end of the other section so that said adjacent end 40 constitutes a stop, a load carriage movable along the trackway, and means normally supporting said movable section with its end 45 on substantially the same level as the end of the adjacent section, said means consisting of a spring set to support said movable section under the weight of the carriage but to be depressed under the weight of the carriage 50 and load to permit the movable section to be moved downward.

16. A load-transferring means comprising an inclined trackway including two sections arranged end to end and in longitudinal 55 alinement with each other, one of said sections being mounted whereby its end is movable to a point below the level of the adjacent end of the other section, a load carriage on the trackway, means whereby the 60 carriage and load move the movable track section downward to drop the carriage below the level of the said adjacent end of the other section, and means whereby when the carriage is relieved of its load the movable 65 track section is automatically raised to nor-

mal position to permit the carriage to gravitate on the main track section.

17. A load-transferring means comprising an inclined trackway, a load carriage on the trackway, means for suspending a load from 70 said carriage, and means at the upper end of the trackway operable by the weight of the carriage and load to hold the carriage stationary on the trackway.

18. A load-transferring means comprising 75 a trackway including two sections arranged end to end in longitudinal alinement with each other, means whereby one of said sections is movable downward to carry its end below the level of the end of the adjacent 80 section, a load carriage on the trackway and spring means for normally maintaining the movable section on a level with the main track section.

19. A load-transferring means comprising 85 a trackway including two sections arranged end to end and in longitudinal alinement with each other, means whereby one of said sections is movable downward to bring its end below the adjacent end of the other 90 section, a load carriage on the trackway and means for normally maintaining the movable section on a level with the other section.

20. A load-transferring means comprising 95 a trackway including two sections arranged end to end in longitudinal alinement, means whereby one of said sections is movable to bring its end below the adjacent end of the other section, a load carriage traveling on 100 the trackway, and means for supporting the movable track section under the weight of the carriage but permitting the said section to be moved down under the weight of the carriage and load so that the adjacent end of 105 said other section constitutes a stop.

21. A load-transferring means comprising a trackway including two sections arranged end to end in longitudinal alinement, means whereby one of said sections is movable to bring its end below the adjacent end of the other section, a load carriage traveling over 110 the trackway, and spring means for supporting the movable track section under the weight of the carriage but permitting the 115 said movable section to be depressed under the weight of the carriage and load.

22. A load-transferring means comprising 120 spaced standards, inclined spaced bridge members connecting the standards, parallel trackways on the bridge members each including a main section and a movable section arranged end to end and in longitudinal alinement, means whereby the movable section may be moved downward to bring 125 the end adjacent the other section below the adjacent end of said other section, a load carriage depending between the trackways and having running wheels on the trackways, and means for yieldingly supporting 130

the movable track section on a level with the main section.

23. A load-transferring means comprising a trackway, a carriage movable along the trackway and having a fall rope adapted to hoist and suspend the load from the carriage, a latch for locking the carriage to the trackway, and means for automatically operating said latch to lock the carriage to the trackway when the carriage is loaded and to re-

lease the carriage when the latter is relieved of its load.

In testimony whereof I have hereunto signed my name in the presence of two subscribing witnesses.

THOMAS SPENCER MILLER.
